UNITED STATES PATENT OFFICE.

JOHN C. HOLSON, OF ORD, NEBRASKA.

DENTAL SPRAYING APPARATUS.

SPECIFICATION forming part of Letters Patent No. 739,674, dated September 22, 1903.

Application filed October 24, 1902. Serial No. 128,584. (No model.)

To all whom it may concern:

Be it known that I, JOHN C. HOLSON, a citizen of the United States, and a resident of Ord, in the county of Valley and State of Nebraska, have invented a new and Improved Dental Spraying Apparatus, of which the following is a full, clear, and exact description.

This invention relates to a valvular nozzle adapted to be connected to a hose or other source of water-supply.

The present improvements lie in a special construction of nozzle-body and in the peculiar arrangement therewith of a valve to be controlled at will by the person manipulating the nozzle.

This specification is a specific description of one form of the invention, while the claim defines the actual scope thereof.

Reference is to be had to the accompanying drawings, forming a part of this specification, in which similar characters of reference indicate corresponding parts in both the figures.

Figure 1 is a side elevation showing the invention applied to a dental engine, and Fig. 2 is an enlarged longitudinal section of the nozzle.

By way of illustration I have shown the invention applied to a dental engine for spraying water on the tool and tooth during operation.

c indicates the flexible shaft, *e* the barrel or handpiece, and *d* the tool.

a b indicate the water-supply.

f indicates the body of the nozzle, to which the tube *b* leads, and *g* indicates any suitable means for securing the nozzle alongside of the handpiece *e*.

The body *f* has at its inner end a nipple to engage the hose *b*, this nipple having the passage *f'* formed therein, and said passage extending into the body of the nozzle and terminating in a valve-seat *f''*. This valve-seat lies in the valve-chamber *f''*, and from said chamber a passage *f''* leads forward to the front end of the nozzle. At said end the body *f* is formed with a reduced threaded portion *f''*, on which is fastened the mouthpiece *h*.

In the valve-chamber *f''* is located the valve *i*, the stem of which passes laterally of the nozzle to the outside thereof. The valve-chamber *f''* extends to the outer wall of the nozzle, and in the outer portion of the chamber is fastened a cap *i'*, closing the chamber and having the stem of the valve *i* passed snugly yet movably therethrough. On the outer end of the stem of the valve *i* are formed two collars *i''*, with which is loosely engaged the end of a finger-lever *k*. This lever is fulcrumed intermediate its ends on the outside of the nozzle, and a spring *k'* presses outward its second end.

The valve *i* controls communication from the passage *f'* to the passage *f''*, and hence by operating this valve the nozzle may be opened or closed at will. The spring *k'* holds the valve seated, and owing to the arrangement of parts, as shown, the nozzle may be manipulated and operated with great convenience.

Having thus described my invention, I claim as new and desire to secure by Letters Patent—

A valvular nozzle, comprising a body having a valve-chamber therein, said chamber extending to the outer wall of the body and having a valve-seat in its inner portion, the body also having passages leading from its inner end to the valve-chamber and from the valve-chamber to the outer end of the body, a cap secured in the outer portion of the valve-chamber to close the same, a valve working on the seat in the chamber and having its stem passed loosely through the cap, a finger-lever fulcrumed on the outside of the nozzle-body and connected to the stem of the valve, and a spring pressing the lever normally to close the valve.

In testimony whereof I have signed my name to this specification in the presence of two subscribing witnesses.

JOHN C. HOLSON.
